(57) **CLAIM**

The ornamental design for a spinning top toy, as shown and described.

DESCRIPTION

FIG. 1 is a front elevational view of the spinning top toy;
FIG. 2 is a rear elevational view thereof;
FIG. 3 is a left-side elevational view thereof;
FIG. 4 is a right-side elevational view thereof;
FIG. 5 is a top plan view thereof;
FIG. 6 is a bottom plan view thereof;
FIG. 7 is a front, top and right side perspective view thereof;
FIG. 8 is a disassembled front, top and right side perspective view thereof;
FIG. 9 is a disassembled rear, bottom and left side perspective view thereof;
FIG. 10 is a top plan view as in FIG. 5, but omitting the oblique hatching from the transparent portion to clarify the underlying structures;
FIG. 11 is a perspective view as in FIG. 7, but omitting the oblique hatching from the transparent portion to clarify the underlying structures;
FIG. 12 is a top plan view as in FIG. 5, but omitting the structures underlying the transparent portion to clarify the overlying transparent structures; and,
FIG. 13 is a perspective view as in FIG. 7, but omitting the structures underlying the transparent portion to clarify the overlying transparent structures.
